CONVERTIBLE SCARF

Dorothy B. Rossant, New York, N.Y.

Application January 29, 1949, Serial No. 73,535

2 Claims. (Cl. 2—91)

1

This invention relates to a novel type of scarf-like piece of wearing accessory which may be worn in various ways. The prime object of the invention is to provide a wearing accessory of simple construction and inexpensive manufacture which can be worn as, or converted at will into, the following types of accessories: (a) a scarf or muffler of the type known as a jabot; (b) a similar form used mostly by men and known as an Ascot tie or a stock tie; (c) a halter or sleeveless blouse; (d) a simple scarf; (e) a bandeau or head covering.

The novel wearing accessory is shown, together with some of the various forms of wear in which it is convertible, in the accompanying drawing, wherein:

Fig. 1 shows the novel wearing accessory in outstretched condition;

Fig. 2 shows it folded in half, as the first step in converting the accessory into various wearing forms;

Fig. 3 illustrates the conversion of the novel accessory into a jabot or Ascot tie (this showing the first steps; the conversion being completed in Fig. 4);

Fig. 4 likewise illustrates the conversion of the novel accessory into a jabot or tie, this figure showing the completed conversion, shown in its first stages in Fig. 3;

Fig. 5 is a front view of the novel accessory being worn as a halter or sleeveless blouse;

Fig. 6 is the rear view of the blouse or halter conversion of Fig. 5; and

Fig. 7 shows a slightly modified form of the novel wearing accessory.

The novel convertible wearing accessory which is fabricated of chiffon, or other silk, rayon or cotton fabric of soft texture, is shown when fully stretched out, in Fig. 1. As there shown, the novel accessory is of square outline, although it may have any other rectangular or substantially rectangular formation. As a matter of fact, the novel accessory need not be quadrilateral; a modification is shown in Fig. 7 which is formed from a blank of nonquadrilateral or irregular outline. But for facility in illustration the novel accessory is shown in Fig. 1 (and Fig. 2) as formed from a square blank.

Irrespective of the shape of the blank from which it is formed, the novel wearing accessory of this invention has a center portion 10 of major area and four corners, more accurately, corner enlargements, 11, 12, 13 and 14, of minor area. The enlargements result from large cut-outs, 15, 16, 17 and 18, one at each of the four sides of the blank.

2

The first step in converting the novel accessory into the various wearing forms mentioned above (and described below) is to fold the same on a diagonal line, such as the diagonal 19, Fig. 1 running from corner enlargements 12, 14. The accessory is shown in Fig. 2 in its folded condition.

The conversion of the novel accessory (folded, Fig. 2) into a jabot or Ascot tie is shown in Figs. 3, 4. The first step that the wearer takes is to hold the folded accessory in front of her with the double corner enlargement 13 (11), best shown in Fig. 2, centered as shown in Fig. 3 and with the other two corner enlargements held outstretched in either hand. This initial step does not appear in Fig. 3; but the corner enlargement 12 (which is to the right of the double corner enlargement 13 (11) in Fig. 2) would be held in her left hand, designated L in Fig. 3. The other corner enlargement 14 would be held in her right hand R. The two ends 12, 14 are then encircled around the neck so that the corner enlargement 14 is now held in her left hand (L) and the corner enlargement 12 in her right hand (R), as is shown in Fig. 3.

25 The two ends 12, 14 are then formed into an over-hand or Ascot tie, designated 20 in Fig. 4.

The conversion of the novel accessory (unfolded, Fig. 1) into a halter or sleeveless blouse is shown in Figs. 5—6. The unfolded accessory, Fig. 1, is held by the wearer in front of her with the two upper corner enlargements 11, 12, Fig. 1, in the region of the neck and with the two lower corner enlargements 13, 14, Fig. 1, in the region of the waist. The said two upper ends 11, 12 Fig. 1, are tied to form a loose knot at the back of the neck, designated 21 in Fig. 6; the said two lower ends, 13, 14, Fig. 1, are tied to form a loose knot at the back, designated 25 in Fig. 6.

As mentioned earlier, the novel convertible wearing accessory need not be square shaped, as shown in Fig. 1; nor need it be quadrilateral. The novel accessory need not have four corner enlargements as is shown in Fig. 1; it may be made with three corner enlargements (as is shown in Fig. 2). In the modification, which may be illustrated by aforesaid Fig. 2, the accessory is formed from a triangular, more accurately, a right-angle triangle, blank. This modification may, however, be formed from an irregular blank as is shown in Fig. 7. In the latter figure there is a center enlargement 23 and two end enlargements 22, 24, making three enlargements in all. The end enlargements 22, 24 are separated from the center enlargement 23 by side cut-outs, respectively, 26, 27. It will be observed that the corner of the blank opposite center enlargement

23 has been cut away by a line 29 which is spaced from, but parallel to, the diagonal 19.

The corner enlargements, such as 11, 12, 13 and 14 in Fig. 1; 13, 12, 14 in Fig. 2; and 22 and 24 in Fig. 7, have been shown, for facility in illustration, with straight edges. But it will be understood that they may be made with curved edges as has been shown at center enlargement 23, Fig. 7.

I claim:

1. A convertible scarf comprising a piece of light weight scarf material of substantially square outline, said material having a central portion substantially square in shape, constituting a major area and a plurality of corner enlargements constituting minor areas, said corner enlargements of minor areas each substantially square in shape, said corner enlargements being separated by side cut-outs, whereby when said scarf is folded on a diagonal line a pair of coterminous corner enlargements centrally disposed and a diagonally folded single corner enlargement at each end are formed, said coterminous central enlargements and said end enlargements being, respectively, separated by said cut-outs, said coterminous central enlargements being adapted to cover the front torso of the wearer with the material between said end enlargements in encircling relation about the neck of the wearer, said end enlargements being adapted to be formed into an over-hand knot disposed in superposed relation to said centrally disposed coterminous enlargements.

2. A convertible scarf comprising a piece of light weight scarf material of substantially square outline, said material having a central portion substantially square in shape, constituting a major area and a plurality of corner enlargements constituting minor areas, said corner enlargements of minor areas each substantially square in shape, said corner enlargements being separated by side cut-outs, whereby when said central portion of major area is held in front of the wearer with a pair of said corner enlargements at the neck of the wearer and a pair of corner enlargements at the waist of the wearer, the first said pair of enlargements may be formed into a knot at the back of the neck of the wearer, and the second said pair of enlargements may be formed into a knot at the back of the waist of the wearer.

DOROTHY B. ROSSANT.
